(57) **CLAIM**

The ornamental design for cooper's shave, as shown and described.

DESCRIPTION

FIG. 1 is a perspective view of a first embodiment of the cooper's shave of this invention.

FIG. 2 is a top plan view of the design for the cooper's shave shown in FIG. 1.

FIG. 3 is a front elevation view of the design for the cooper's shave shown in FIG. 1.

FIG. 4 is a bottom plan view of the design for the cooper's shave shown in FIG. 1.

FIG. 5 is an enlarged side view of the cooper's shave shown in FIG. 1; the opposite side of which is a mirror image; and,

FIG. 6 is an enlarged side view showing an alternative embodiment of the ornamental design for a cooper's shave shown in FIG. 1; the opposite side of which is a mirror image.

The top, front, bottom and perspective views for the alternative embodiment disclosed in FIG. 6 correspond to FIGS. 1 through 4.

1 Claim, 3 Drawing Sheets
